UNITED STATES PATENT OFFICE.

DANIEL F. SMITH AND DANIEL L. SAWYER, OF HAVERHILL, MASSACHUSETTS, ASSIGNOR OF ONE-THIRD THEIR RIGHT TO ANDREW F. STOWE, OF SAME PLACE.

DESIGN FOR A PAPER-CLIP.

Specification forming part of Design No. 7,510, dated June 30, 1874; application filed June 17, 1874.
[Term of Patent 14 years.]

To all whom it may concern:

Be it known that we, DANIEL F. SMITH and DANIEL L. SAWYER, of Haverhill, in the county of Essex, State of Massachusetts, have invented a Design for a Paper-Clip or Paper-Hook, of which the following is a specification:

The nature of our design is represented in the accompanying drawings, to which reference is made.

A represents a plate surmounted by a figure, representing a clown as holding the disk A in front of him. The nose of the clown forms a lip, B, as shown in Figure 2 of the drawings, which is a side elevation of our device. C is a bent pin or hook, which engages with the nose of the figure. The plate A,

which is made shield-shaped, may have around its edge a raised molding, although this does not form an essential feature of our design.

What we claim as our invention is—

A design for a paper-clip or paper-holder, in which is represented an animal figure supporting in front of it a shield, from which a pin, C, engages with its projecting nose.

In testimony that we claim the foregoing we have hereunto set our hands this 11th day of June, 1874.

DANIEL F. SMITH.
DANIEL L. SAWYER.
